UNITED STATES PATENT OFFICE.

WILLIAM J. MALONEY, OF ANSONIA, CONNECTICUT, ASSIGNOR TO THE ANSONIA
O & C CO., OF ANSONIA, CONNECTICUT, A CORPORATION.

DEVICE FOR USE WITH RUBBER-THREAD-WORKING MACHINES.

Application filed December 28, 1924. Serial No. 758,175.

To all whom it may concern:

Be it known that I, WILLIAM J. MALONEY, a citizen of the United States, residing at Ansonia, in the county of New Haven and State of Connecticut, have invented a new and useful Improvement in Devices for Use with Rubber-Thread-Working Machines; and I do hereby declare the following, when taken in connection with the accompanying drawings and the characters of reference marked thereon, to be a full, clear, and exact description of the same, and which said drawings constitute part of this application, and represent, in—

Fig. 1 a face view of a "rubber-post" for a braiding machine, showing my improved safety device.

Fig. 2 a vertical, sectional view of the same.

Fig. 3 a sectional view on the line 3—3 of Fig. 1, enlarged.

Fig. 4 a broken, enlarged, sectional view, illustrating the operation of the device upon the breakage of the rubber thread.

Fig. 5 a broken, plan view, illustrating the application of my invention to a rubber-thread weaving loom.

Fig. 6 a side view of the same, partly in section.

This invention relates to improvement in devices in connection with rubber-thread-working machines, whether those machines be in the form of braiders for covering one or more strands of rubber thread with fabric, or in looms in which a number of threads are woven to form a flat web. In the manufacture of elastic textile goods, the rubber threads are wound under tension on spools commonly called "warp beams". The rubber is generally wound in parallel rows to the required depth, the number and size of threads depending upon the nature of the material to be produced. In weaving and braiding rubber threads, there will be a cer-

tain amount of breakage of the rubber threads as the said rubber threads are woven or braided under tension. While this breaking may occur at any place on any thread, it is most likely to occur at the place where the actual braiding or weaving action takes place and, in the case of weaving, more frequently in the edge thread, or threads, of the web. When this breakage takes place, difficulty is experienced in ascertaining which thread on the beam has

broken, and difficulty is experienced in rethreading the broken strand. The object of this invention is to provide a device so located as to be visible to the operator and which may also actuate electrically a visible or audible signal, or both, and if desired, in addition thereto, to actuate a stop motion for the machine, and the invention consists in the construction as hereinafter described and particularly recited in the claims.

In Figs. 1, 2, 3 and 4, I have illustrated my invention in connection with the so-called "rubber-post" of braiding machines of usual construction, mounted upon the usual carrier-plate, not shown, and provided at the upper end with a grooved roller 11, over which the rubber thread passes. This post is segmental in cross-section and the thread passes upward through the base 12, which is provided with a clearance opening 13. Pivotedly mounted in the groove of the post is a tubular clamping-member 14, and secured to the screw 15, by which the tube is mounted, is a coiled spring 16 attached to the lower end of a latch-block 17, in the form of a bead, and adapted to closely fit the upper edge of the clamping-tube 14. The screw 15 is insulated from the post. The inner end of the clamping-block is preferably slightly grooved, so that, if desired, during the adjustment of the machine, the block can be moved over one side of the clamping-tube, so as to be temporarily mounted thereon. A rubber thread 18, passing upward through the post and over the roller 11, passes through the clamping-tube and, under normal conditions, passes freely through it. Should this particular thread break beyond the clamping-tube, the tension of the thread will draw the latch-block 17 down into the upper end of the tube and grip the thread against the upper edge of the tube, as shown in Fig. 4 of the drawings, and the edge in position will be immediately visible to the operator. Preferably and as shown, a yoke 19 will be secured to the back of the post, with its ends extending outward on opposite sides of the clamping-tube. The screw 15 is connected by wire 20, which extends down through a perforation 21 in the post and downward through the clearance opening 13, to a visible or audible signal, or to any of the well-

known forms of stop mechanisms. When the thread breaks, the clamping-tube will engage with one of the ends of the yoke, and so close electrical connection to the signals or stop mechanism, and the broken thread is readily located, and is in position for readjustment to the braiding mechanism.

In Figs. 5 and 6 of the drawings, I have indicated the use of my invention to a loom for forming flat web, and in this case, I mount a bracket 22 upon the frame 23 of the loom and below the strands 24 of rubber, which are drawn from the usual warp beam 10. Supported by this bracket, upon a transverse supporting-pin 26, are a series of clamping-tubes 27 like the tubes 14 previously described, and in each is a spring-actuated latch-lock 28. Extending across 15 the bracket, beneath the clamping-tubes, is a metal rod 29, insulated from the bracket and adapted to have an electric wire 30 connected with it, this wire running to a visible or audible signal or stop mechanism. Pref- 20 erably, the threads 24 will pass beneath the supporting-pin 26. If one of the various threads 24 breaks beyond the bracket 22, the release of tension on the thread will draw the latch-block 28 into the outer end of 25 the tube 27 and grip the thread, and the tension of the thread will cause the tube to drop into contact with the rod 29 and so close an electrical circuit to a visible or audible signal, or to the stop mechanism or all of 30 them, and the dropping of the tube will be readily perceptible to the operator, so that the broken thread is at once located.

In any use, as shown, of my invention, the breakage of a rubber thread adjacent to the 40 braiding or weaving mechanism is at once noted, and the broken thread is held at a position convenient for re-adjustment.

I claim:

1. In a rubber-thread-working machine, a 45 clamping-mechanism through which a rubber thread may freely pass in one direction, and adapted, when the tension on the thread is released, to hold the thread against movement in the opposite direction, and means 50 operated by the movement of said clamping mechanism to actuate a signal.

2. In a rubber-thread-working machine, a 55 clamping-tube through which the thread extends, and a clamping-block connected with the tube and adapted, when the tension on the thread is released, to grip the thread against the edge of the said tube.

3. In a rubber-thread-working machine, a

clamping-tube through which the thread ex- 60 tends, and a spring-actuated clamping-block connected with the tube and adapted, when the tension on the thread is released, to grip the thread against the edge of the said tube.

4. In a rubber-thread-working machine, a 65 clamping-tube through which the thread extends, a clamping-block connected with the tube and adapted, when the tension on the thread is released, to grip the thread against the edge of the said tube, and means operated by the movement of said tube to actuate 70 a signal.

5. In a rubber-thread-working machine, a 75 clamping-tube through which the thread ex- tends, a clamping-block connected with the tube and adapted, when the tension on the thread is released, to grip the thread against the edge of the said tube, and an electrical circuit closed by the movement of said clamping-tube.

6. In a rubber-thread-working machine, a 80 clamping-tube through which the thread ex- tends, a clamping-block connected with the tube and adapted, when the tension on the thread is released, to grip the thread against the edge of the said tube, and an electrical 85 circuit connected with a stop mechanism and closed by the movement of said clamping-tube.

7. In a rubber-thread-working machine, the combination with the "rubber-post" of 90 a clamping-tube pivotally connected therewith and through which a rubber thread passes, a clamping-block yieldingly connected with said tube and adapted, when tension on the thread is released, to grip the 95 thread against the end of the tube.

8. In a rubber-thread-working machine, the combination with a "rubber-post" of a 100 clamping-tube pivotally connected thereto, a clamping-block yieldingly connected with 105 said tube and adapted to seat upon the upper end thereof, a yoke connected with the post and projecting forward on opposite sides of the tube, the said tube electrically connected with a breakage indicator, and adapted, upon the release of tension of the thread, to move into engagement with said yoke, whereby the circuit to the indicating means is closed.

In testimony whereof, I have signed this 110 specification in the presence of two subscribing witnesses.

WILLIAM J. MALONEY.
